CLOTH-CUTTING MACHINE

William Bangser, New York, N. Y., assignor to
 H. Maimin Company, Incorporated, a corpora-
 tion of New York

Application April 16, 1938, Serial No. 202,430

18 Claims. (Cl. 51—249)

This invention relates to cloth-cutting machines of the reciprocating knife type and particularly to means for sharpening the knives of such machines.

Various means have been proposed for sharpening the knives of cloth-cutting machines of the reciprocating knife type by power-driven means, but all of them, so far as I am aware, have been objectionable because the stones have been so mounted as to impair the full cutting capacity of the machine and obstruct the operator's view when not in use. In accordance with the present invention I have so mounted the stones that when not in use they are swung forward away from the knife and upward, thus permitting the operator to employ the full capacity of the machine for the thickest lays, and, also permitting him an unobstructed view of the line of pattern mark at the point of cutting. Doing this has involved the provision of means for moving the stones outside of the presser foot guard at the completion of the grinding operation and for moving them inside of the guard for grinding.

During cutting the stones preferably, carried on swinging arms, are swung forward of the guard and held well above and beyond the upper end of the knife. To sharpen, the stones are rotated, swung on their arms around the guard and into grinding contact one with either side of the knife.

The stones, still rotating, are moved down the length of the knife edge, the traverse reversed, and are then swung out into inoperative position, thus completing the grinding cycle. In the preferred embodiment of my invention this cycle requires the action of the operator for its initiation only, the driving mechanism being automatically thrown out of operation at the end of the cycle.

As the grinding takes place without removing the presser foot the cycle cannot be completed unless the presser foot is in its lowermost position. Should the operator neglect to lower the presser foot to its lowermost position before initiating the grinding cycle, the machine would be seriously damaged. I have, therefore, provided several means for avoiding this accident. One, arranging the starting mechanism so that the grinding cycle cannot be initiated until the presser foot has been lowered; two, providing means for automatically interrupting the downward movement of the stones immediately before engagement with the presser foot; and three, making the presser foot guard extensible and movable with the stone carriage.

In order that the stones shall grind the edge of the knife without engaging each other, one is

placed slightly in advance of or below the other. If both faces of the knife are to be ground throughout their entire lengths and the point of the chopping edge or bottom bevel ground, the forward or lower stone must pass beyond the 5 end of the knife. As the stones are spring-pressed toward the knife in order to take up wear the stone passing the end of the knife swings in and on the upward stroke forms a burr on the bottom bevel which seriously interferes with effi- 10 cient cutting. To avoid this difficulty I provide one double and one single stone, with the plane of the single stone intermediate the planes of the two sections of the double stone. The upper section of the double stone bears against the 15 knife when the lower element has passed the lower edge and this prevents the latter from swinging under the knife and forming a burr.

In the accompanying drawings I have illustrated two different mechanisms for moving the 20 stones through the grinding cycle. In the first, the mechanism is driven from the motor which reciprocates the knife; in the second, a separate driving motor is provided. In these drawings Figure 1 is a side elevation of a conventional 25 cloth-cutting machine of the reciprocating knife type showing in vertical section a grindstone actuating mechanism driven from the main motor of the machine; Figure 2 is an elevation of the upper end of the machine of Figure 1 viewed from 30 the other side; Figure 3 is an end elevation of that part of the machine shown in Figure 2; Figure 4 is a detail of the starting mechanism showing the means for preventing starting until the presser foot is in its lowermost position; Figure 5 is a 35 transverse section taken along line 5—5 of Figure 3; Figure 6 is a vertical section on a somewhat enlarged scale taken along line 6—6 of Figure 1; Figure 7 is a transverse section taken along line 7—7 of Figure 6; Figure 8 is a transverse section 40 taken along line 8—8 of Figure 1; and Figure 9 is a transverse section taken along line 9—9 of Figure 6. Figure 10 is a side elevation of a conventional cloth-cutting machine of the reciprocating 45 knife type provided with a stone-actuating mech- 45 anism driven by a separate motor; Figure 11 is a longitudinal vertical section on a somewhat enlarged scale of the grindstone actuating mech- 50 anism of Figure 10; Figure 12 is a detail of the switch which controls the actuating motor; Figure 13 is a vertical section taken along line 13—13 of Figure 11; Figure 14 is a transverse section taken along line 14—14 of Figure 11; Figure 15 is a transverse section taken along line 15—15 of Figure 11; Figure 16 is a detail showing the rela- 55

tion between the knife and the grindstone at the lower end of the stone traverse; and Figure 17 is an elevation, partly in section, of a modified form of presser foot and guard.

5 I shall refer first to the machine illustrated in Figures 1 through 9. The cloth-cutting machine there illustrated comprises the usual base 1 on which is mounted a standard 2 carrying a motor 3 and a motor housing 4. A knife 5 is mounted 10 for reciprocation in a vertical slot in the forward edge of the standard. The reciprocating mechanism comprises a cross-head 6, a pitman 7 and a crank 8 mounted on a fly-wheel 9 on the motor shaft. The operation of the motor is controlled by a switch 10 and the whole machine 15 guided by means of handle 11. Mounted for vertical adjustment immediately in front of the knife 5 is a presser foot 12 carried by a guard 13. The foregoing is standard construction and of itself 20 forms no part of the present invention.

I shall now describe how the grindstones are mounted and swung. Mounted on the front of the motor housing is a fixed grinder frame 15 having vertical guideways 16 in which is slidably mounted a grinder slide 17 closed at its lower end by a plate 18 extending inward toward the motor housing. On the inner end of this plate 18 are mounted two vertical spindles 19 carrying at their lower ends plates 20 on which grindstone studs 21 are mounted, these studs carrying grindstones 22 and 23. A coil spring 24 encircles each spindle, fixed at one end to the spindle, and at the other to the plate 18. These springs normally urge the plates 20 to assume the position 25 shown in Figure 8 and in dotted lines in Figure 1 with the stones in grinding contact with the edge of the knife 5. In order to swing the stones out of contact with the knife at the upper end of their traverse and permit them to clear the lower 30 end of the motor housing, I provide two fixed threaded nuts 25 (see Figure 1) between the grinder frame 15 and the motor housing adapted to receive the upper ends of the spindles 19. The upper ends of these spindles are provided 35 with threads 26 of large pitch so that in passing through the nuts, with which they make threaded engagement, the spindles are rotated through angles of something more than 150° against the action of springs 24 and the stones thereby swung 40 outward to assume a position immediately below the grinder frame, as illustrated in Figures 1, 2, 3, 6 and 7. In this position they do not obstruct the vision of the operator.

I shall now describe the mechanism which rotates the grindstones. Journaled within the slide 17 is a square shaft 28 on the lower end of which is fixed a pinion 29 which, through gears 30, 30' and 31, rotates the stone 22 in a clockwise direction, as viewed in Figure 8, and through gears 32, 33, 33' and 34 rotates stone 23 in a counter-clockwise direction. The gears 30 and 30' are fixed upon the same stud and rotate together. The same is true of gears 33 and 33'. Square shaft 28 passes slidably through a square hole 36 in a bevel pinion 35 journaled in a plate 36 mounted on the fixed grinder frame 15. Bevel pinion 35 meshes with another bevel pinion 37, journaled in the frame 15, on the shaft of which is fixed a pinion 38 meshing with gear 39, also 45 journaled on the grinder frame, which meshes in turn with a pinion 40 journaled in a rocker arm 41 pivoted at 42 and coaxial with friction drive wheel 43 designed to make frictional driving engagement with the fly-wheel 9 of the motor.

70 When the friction wheel 43 is swung into contact

with the rotating fly-wheel 9 by means to be described presently, the grindstones are rotated through the various gear trains just described.

I shall now describe the mechanism by means of which the grindstones are traversed while 5 rotating. Mounted on the outer face of the grinder frame 15 are two sprockets 45 around which pass a chain 46. One link of this chain is provided with a roller 47 lying within a slotted block 48 fixed to the upper end of the slide 17. 10 Movement of the chain thus reciprocates the slide 17 in its guideway 16 and with the slide the grindstones reciprocate likewise. The stones are positively rotated throughout the reciprocation of the slide by virtue of the fact that the square 15 shaft 28 can move vertically with reference to the pinion 35 while, at all times, being driven by that pinion. The chain is driven through the following reducing gear train: a pinion 49 fixed to and rotating with the gear 39 meshes with a 20 gear 50 to which is fixed a pinion 51 meshing with a gear 52 on the shaft of the lower sprocket 45. Thus rotation of the friction drive wheel 43 not only rotates the grindstones, but causes them to traverse the length of the knife, that is the effective cutting range of the knife, and back. 25

I shall now describe how the grinding cycle is initiated and how the mechanism which effects it is automatically thrown out of operation at the end of one cycle. The cycle is initiated 30 through the operation of a trigger 54 mounted on one side of the grinder frame 15. This trigger is provided with a trigger shaft 55 journaled within a sleeve 56. At the inner end of the trigger shaft 55 is fixed a short arm 57 on 35 which is pivotally mounted a longer arm 58 urged toward the machine by means of coil spring 59. The lower end of the arm 58 is connected to the rocker arm 41 by means of a toggle link 60. With the parts arranged as shown in Figure 4 with 40 the arm 57 on the trigger shaft held fixed by means of a trigger latch, to be described presently, the toggle link is so positioned that the spring 59, acting through arm 58, holds the friction drive wheel 43 out of contact with the fly-wheel 9 of the motor. In order to move the friction wheel 43 into driving contact with the fly-wheel, 45 the trigger, trigger shaft and arm 57 are swung to the right, as viewed in Figure 4, until the lower toggle joint passes to the right of a line extending through the upper toggle joint and the pivot 42 of the rocker arm 41. Thereupon the spring 59 snaps the friction wheel 43 into driving contact with the fly-wheel and holds it there. Mounted on the trigger is a trigger latch 62, 55 the lower arm of which engages a trip 63 mounted on the front of the slide 17 and normally holds the trigger in the position shown in Figures 3 and 4, that is, with the driving wheel out of contact with the fly-wheel. The upper arm of the latch is normally urged away from the trigger 60 by means of a leaf spring 64.

The apparatus just described operates as follows: In order to initiate the grinding cycle, the operator grasps the upper ends of the trigger and trigger latch between the thumb and forefinger and draws them together, thus freeing the latch from the trip. The trigger thus freed is then swung to the right to snap the drive wheel into contact with the fly-wheel, as described before. If we assume that the fly-wheel is rotating, the gear trains are set in motion and three things happen: one, the grindstones are rotated, two, the slide moves downward, and three, cooperation between the fixed nuts 25 and the 70

threaded ends 26 of the spindles swings the rotating grindstones around the presser foot guard so that the springs 24 may then move them into contact with the edge of the knife. Through movement of the chain 46 the slide 17 carries the stones to the bottom of the knife and then reverses the traverse. On the upward movement, engagement of the threaded ends 26 of the spindles with the nuts 25 swings the stones 10 out around the presser foot, thus reversing the movement which took place at the initiation of the cycle. When the slide reaches its uppermost position, however, as shown in Figure 6, where continued operation of the mechanism would repeat the cycle just described, the trip 63 engaging the lower end of the latch 62 throws the trigger to the left and through the action of the toggle 60 snaps the driving wheel out of contact with the rotating fly-wheel. In order that there should be no over-running of the mechanism, I provide a fixed brake shoe 65 which engages the driving wheel 43 when it is swung out of contact with the fly-wheel.

I shall now describe the means which I have devised which make it impossible to operate the grinding mechanism until the presser foot has been lowered into contact with the base 1. As shown best in Figure 4, the rocker arm 41 which carries the friction drive wheel 43 is provided 30 with a vertically extending arm 66 provided with an inturned end 67. When the presser foot is in any raised position, the guard 13 projects beyond the end 67 of the arm 66. Thus should the operator attempt to swing the trigger so as to throw the grinding mechanism into operation he would be unable to effect his purpose because the end 67 would bear against the guard 13 and make it impossible for the toggle 60 to snap the drive wheel 43 into contact with the fly-wheel. 40 When the presser foot is resting upon the base of the machine, however, the upper end of the guard 13 is not so high that the end 67 of the arm 66 may not be swung over it.

As shown in Figures 6 and 16, the grindstone 45 22 comprises two axially separated sections mounted on a single stud, whereas grindstone 23 comprises a single section, the plane of which is intermediate that of the two sections of the other stone. At the lower end of the traverse 50 the stones occupy the position relative to the knife shown in Figure 16, the knife being shown at the lower end of its reciprocation. It will be noted that the lower section or element of the stone 22 has completely passed the knife and were this section separately mounted, the action 55 of the spring urging it into grinding contact with the stone would tend to swing it beyond the edge of the bottom bevel so that on the return movement a burr would be turned on the bottom bevel. As the sections of the stone 22, however, 60 are rigidly connected, being mounted on a single stud, this action cannot occur, the upper section bearing against the knife and holding the lower one in alignment. It would be possible, 65 of course, to substitute a non-grinding element for the upper section, but I have found it more satisfactory to employ two grinding elements.

I shall now describe the modified form of actuating mechanism illustrated in Figures 10 through 15. The cloth-cutting machine itself, shown in these figures, is precisely the same as the one illustrated in the other figures and need not be described again.

I shall first describe how the grindstones of 75 this modified mechanism are mounted and

swung. Pivotedly mounted at 70 on the front of the motor housing is a frame 71 having trackways 72 on which is slidably mounted a grinder slide 73 closed at its lower end by plate 74 extending inward toward the motor housing. 5 Pivotally mounted at 75 on the lower face of plate 74 are a pair of arms 76 extending inward toward the machine and carrying at their ends grindstones 77 which are, so far as the stones are concerned, precisely like the grindstones 22 10 and 23 described in connection with the other form of device. Extending upward through arcuate slots 78 in the plate 74 are pins 79 to which are pivotally connected curved arms 80 the inner ends of which are reduced in width to form 15 tongues 81 and shoulders 82. The tongues 81 overlap and are straddled by the bifurcated end of an arm 83 pivotally mounted on a cross bar 84 carried by the slide 73. The curved arms 80 are connected by means of a coil spring 85 which 20 urges the arm 76 and the stones 77 toward each other and into contact with the edge of the knife during the grinding operation, as illustrated in dotted lines in Figure 14. The upper end of the arm 83 carries a roller 86 which, when in engagement with the rear wall of the frame 71, 25 swings the bifurcated lower end of the arm 83 against the shoulders 82 and, through the curved arms 80, swings the arm 76 and the stones 77 apart, as shown in Figures 14 and 15. 30

I shall now describe the mechanism which rotates the grindstones. Mounted on the slide 73 is a motor 89 controlled by a switch 90 operated by means of a switch arm 91. A pinion 92 on the motor shaft meshes with a gear 93 on a 35 shaft 94, the lower end of which carries a gear 95 which, through gear trains 96, 97 and 98, and 99, 100 and 101 carried by the plate 74 rotates the stones.

I shall now describe the mechanism for traversing the grindstones. Mounted on the inner face of the slide 73 are sprockets 102 around which extends a chain 103. One link of this chain is pivotally connected to a bar 104 pivoted at 105 to the frame 71. The lower sprocket 102 is fixed 45 to a shaft 106 on which is journaled a bevel gear 107 meshing with a bevel pinion 108 fixed on shaft 94. A pinion 109, integral with gear 107, meshes with an idler gear 110 which, through pinion 111 fixed to it, drives a gear 112 splined to the shaft 50 106. Through the reducing gear train just described the motor 89 drives the lower sprocket 102 and the chain 103. Movement of the chain, acting through bar 104 causes the slide 73, carrying the motor, the chain, the various gear 55 trains and the stones to move relative to frame 71. As shown in Figures 10 and 11, the frame 71 and all of the grinding mechanism carried by it is held at an angle to the vertical during normal cutting operations with the stones beyond the 60 presser foot guard and above the handle of the machine. The frame is held in this position by means of an arm 115 pivotally mounted on the motor housing at 116 and normally held vertically in the dotted line position of Figure 10 65 by means of a spring 117. The outer end of the arm 115 is provided with jaws 118 designed to engage a roller 119 on the bar 84 in a manner to be described preesntly.

The apparatus just described operates as follows: The operator swings switch arm 91 down to close the switch 90 and start the motor 89. As the slide 73 moves downward, the stones rotating, the arm 115 is swung about its pivot 116 and the frame 71, urged by a spring 120, tends 75

to assume a vertical position. In the downward movement of the slide the roller 86 moves out of contact with the inner face of the frame 71 rolling along a cam surface 121 thus permitting 5 spring 85 to swing the stones into contact with the knife, the stones having meanwhile passed within the presser foot guard. The stones continue their downward traverse rotating in grinding contact with the knife blade and then reverse 10 their travel due to the action of the chain 103. On the upward traverse the operations performed on the downward traverse are reversed. Roller 119 enters between the jaws 118 of the arm 115 just as roller 86 engages cam surface 15 121. Thus as the frame 71 is swung outward about its upper pivot 70, the stones are swung out on their arm 116 and pass the presser foot guard. In order to stop the mechanism at the completion of a single grinding cycle, one link of 20 the chain 103 is provided with a lug 122 which engages a pin 123 on the switch arm extending through a slot 124 in the slide 13. The path of the lug 122 being along an arc of smaller radius of curvature than the path traversed by pin 123, 25 the lug and pin are disengaged at the moment the switch is opened. During the grinding operation the knife should be reciprocating.

In order that the stones may not necessarily remain in their widest spaced relation when not 30 in use, I provide an opening 125 in the back of the frame 71 through which the roller 86 may project and permit the spring 85 to draw the stones closer together than they otherwise would be so as not to interfere with the vision of the operator.

35 I have provided the grinding mechanism illustrated in Figures 1 through 9 with a safety device which makes it impossible for the operator to start the grinding action if the presser foot is not in its lowermost position. I have provided 40 the grinding mechanism shown in Figures 10 through 15 with a different type of safety device. This device although permitting the operator to start the grinding mechanism with the presser foot in elevated position, nevertheless automatically throws the switch and stops the mechanism before the stones reach the presser foot. This safety device consists of a rod 126 terminating at its upper end in a yoke 127 which straddles and is pivotally connected to the switch arm 45 91. The lower end of the rod slidably engages a hole in the plate 14 and terminates in a crooked end 128. When the operator swings the switch arm 91 downward to close the switch and initiate the grinding cycle the crooked end 128 of the rod 50 126 is moved into the dotted line position shown in Figure 10, just below the stones. If, during the downward traverse of the stones the end of the rod 126 should engage the presser foot, inadvertently left in raised position, the switch 55 60 would be immediately opened and the mechanism stopped before any damage could be done.

In Figure 17 I have illustrated the third safety device invented by me. This comprises a telescoping and extensible presser foot guard. The presser foot 130 is mounted on the end of a square rod 131 which fits within a square sleeve 132 closed at its upper end. A coil spring 133 connects the upper end of the rod 131 with the upper closed end of the sleeve 132 and tends to hold the 65 70 presser foot in abutment with the lower and open end of the sleeve 132. The sleeve 132 and the rod 131 constitute the presser foot guard. This presser foot and guard are mounted on the machine in the usual way and adjusted for the particular lay being cut. When used on a machine 75

employing either type of grinding mechanism described in this application, but lacking any other safety device, the stone mountings descending in the downward traverse of the grinding mechanism engage the presser foot and, acting against 5 the spring 133, cause the rod 131 to slide downward relative to the fixed sleeve 132. On the return traverse of the stones, the presser foot follows them, being moved upward by the retractile spring 133. After the grinding, the presser foot 10 is in the same position of adjustment as it was before.

In using either of the grinding mechanisms described, the machine must, of course, be first removed from the cloth. Unless an extensible 15 presser foot guard is employed the presser foot must be set in its lowermost position before the grinding cycle is begun. When using the grinding mechanism, shown in Figures 1 through 9, it would be impossible for the operator to start 20 grinding until the proper adjustment of the presser foot had been made. Using the form of grinding mechanism shown in the other figures, the grinding operation might be started, but it would be automatically arrested just before the 25 stones encountered the presser foot in the event that the latter had not been previously lowered. When the stones are not in use they are carried above the upper end of the stone and beyond the guard. In this way the full cutting capacity of 30 the stone can be used and the stones, when not in use, do not obstruct the operator's view of the line of the pattern marks at the point of cutting. By the use of the double stone the point of the 35 bottom bevel of the knife is sharpened without the formation of an objectionable burr.

I claim:

1. In a cloth-cutting machine of the reciprocating knife type having a guard, the combination of stones for sharpening the knife mounted, 40 when not in use, beyond the guard, means for rotating the stones, means for moving the stones past the guard while the latter is in operative position and into grinding engagement with the knife, means for traversing the stones along the length of the knife and back, and means for moving the stones past the guard while the latter is 45 still in operative position and into their original position at the end of the grinding cycle.

2. In a cloth-cutting machine of the reciprocating knife type having a guard, the combination of stones for sharpening the knife mounted, when not in use, above the upper end of the knife and beyond the guard, means for rotating the stones, 50 means for swinging the stones around the guard and into grinding engagement with the knife, means for traversing the stones along the length of the knife and back, means for swinging the stones around the guard and into their original 55 position at the end of the grinding cycle, a source of power for the rotating, swinging and traversing means, manual means for applying the power to initiate a grinding cycle and means for automatically turning off the power at the end of the cycle.

3. In a cloth-cutting machine of the reciprocating knife type, the combination of a frame carried by the machine, a slide slidably mounted in the frame, a pair of swinging arms carried by the slide, stones for sharpening the knife mounted 70 on the arms and lying beneath the frame when not in use, means for rotating the stones, means for swinging the arms to bring the stones into grinding engagement with the knife, means for moving the slide relative to the frame to traverse 75

the stones along the length of the knife and back, and means for swinging the stones back into their original position beneath the frame at the end of the grinding cycle.

5. In a cloth-cutting machine of the reciprocating knife type, the combination of means for sharpening the knife comprising two stones, one on either side of the knife, one stone comprising two vertically spaced sections rigidly mounted 10 relative to each other, and the other stone comprising a section lying in a plane intermediate the plane of the two sections of the double stone, means yieldably urging the stones into grinding contact with the knife, means for traversing the stones along the length of the knife until the lower section of the double stone passes beyond the bottom bevel of the knife, the upper section bearing against the knife and preventing the yieldable means from moving the lower section 15 under the bottom bevel of the knife.

20 5. In a cloth-cutting machine of the reciprocating knife type, the combination of stones for sharpening the knife, mountings for the stones, means for moving the stones and their mountings 25 up and down along the knife, a presser foot mounted on a telescoping guard, and a spring urging the guard sections into telescoping condition, the guard extending upon engagement of the stone mountings with the presser foot and 30 returning to its original condition when such engagement ceases.

6. In a cloth-cutting machine of the reciprocating knife type, the combination of a plate movable relative to the knife, a pair of spindles carried by the plate, swinging arms fixed to the spindles, stones for sharpening the knife mounted on the arms, threaded extensions on the spindles, fixed threaded nuts on the machine with which the spindles make threaded engagement when the plate is in its upper position and means for moving the plate vertically relative to the knife, the threads on the nuts cooperating with the threads on the spindles to swing the stones relative to the knife.

45 7. In a cloth-cutting machine of the reciprocating knife type, the combination of a plate movable relative to the knife, a pair of spindles carried by the plate, swinging arms fixed to the spindles, stones for sharpening the knife mounted on the arms, threaded extensions on the spindles, fixed threaded nuts on the machine with which the spindles make threaded engagement when the plate is in its upper position to swing the stones relative to the knife, and means for traversing the plate along the length of the knife and back, the threads on the nuts cooperating with the threads on the spindles to swing the stones into contact with the knife at the beginning of the downward traverse and out of contact with the knife at the end of the upward traverse.

8. In a cloth-cutting machine of the reciprocating knife type having a presser foot and guard, the combination of stones for sharpening the knife mounted upon the machine beyond the guard when not in use, means for rotating the stones, means for moving the stones around the guard and into grinding engagement with the knife, means for traversing the stones along the length of the knife and back, means for moving the stones beyond the guard and into their original position at the end of the grinding cycle, a source of power for the rotating, moving and traversing means, manual means for applying the power, and means rendering said manual means

inoperative unless the presser foot is in its lowermost position.

9. In a cloth-cutting machine of the reciprocating knife type having a motor for reciprocating the knife and a fly-wheel on the motor, the combination of a frame carried by the machine, a slide slidably mounted in the frame, a pair of swinging arms carried by the lower end of the slide, stones for sharpening the knife mounted on the arms, means for rotating the stones, means for swinging the arms to bring the stones into grinding engagement with the knife, a drive wheel mounted on the frame mechanism actuated by the drive wheel for rotating the stones, swinging the arms and moving the slide, and means 10 for throwing the drive wheel into driving engagement with the fly-wheel.

10. In a cloth-cutting machine of the reciprocating knife type having a presser foot mounted on a vertically adjustable guard, a motor for reciprocating the knife, and a fly-wheel on the motor, the combination of stones for sharpening the knife, means for traversing the stones along the length of the knife and back, a drive wheel for actuating the traversing means pivotally 20 mounted adjacent the fly-wheel, a spring and toggle normally holding the drive wheel out of engagement with the fly-wheel, and a manually operated trigger for breaking the toggle to swing the drive wheel into engagement with the fly-wheel.

11. In a cloth-cutting machine of the reciprocating knife type having a presser foot mounted on a vertically adjustable guard, a motor for reciprocating the knife and a fly-wheel on the motor, the combination of stones for sharpening the knife, means for traversing the stones along the length of the knife and back, a drive wheel for actuating the traversing means pivotally mounted adjacent the fly-wheel, a spring and toggle normally holding the drive wheel out of engagement with the fly-wheel, a manually operated trigger for breaking the toggle to swing the drive wheel into engagement with the fly-wheel, and a trip movable with the stones for 40 engaging the trigger at the end of the upward traverse of the stones to throw the drive wheel out of engagement with the fly-wheel.

12. In a cloth-cutting machine of the reciprocating knife type, the combination of a frame 50 carried by the machine, a slide slidably mounted in the frame, a pair of swinging arms carried by the lower end of the slide, stones for sharpening the knife mounted on the arms, means for rotating the stones, means for swinging the arms to bring the stones into grinding engagement with the knife, means for moving the slide relative to the frame to traverse the stones along the length of the knife and back, and a motor mounted on the slide for rotating the stones, swinging the 55 arms, and moving the slide.

13. In a cloth-cutting machine of the reciprocating knife type, the combination of a frame carried by the machine, a slide slidably mounted in the frame, a pair of swing arms carried by the lower end of the slide, stones for sharpening the knife mounted on the arms, means for rotating the stones, means for swinging the arms to bring the stones into grinding engagement with the knife, means for moving the slide relative to the frame to traverse the stones along the length of the knife and back, a pivoted arm carried by the slide and connected with the stone arms, a roller on the upper end of the pivoted arm and a cam on the frame engaging the roller to swing the 70 75

stones out of engagement with the knife at the end of the upward traverse.

14. In a cloth-cutting machine of the reciprocating knife type, the combination of a frame carried by the machine, a slide slidably mounted in the frame, a pair of swinging arms carried by the lower end of the slide, stones for sharpening the knife mounted on the arms, means for rotating the stones, means for swinging the arms to bring the stones into grinding engagement with the knife, means for moving the slide relative to the frame to traverse the stones along the length of the knife and back, a motor mounted on the slide for rotating the stones, swinging the arms, and moving the slide, a manually operated switch for actuating the motor and means for automatically opening the switch at the end of the upward traverse.

15. In a cloth-cutting machine of the reciprocating knife type, having a presser foot and guard, the combination of a frame pivoted upon the machine, a slide slidably mounted in the frame, swinging arms carried by the slide, stones for sharpening the knife carried by the arms, means for holding the lower ends of the frame and slide away from the knife when not in use, means for rotating the stones, means for swinging the frame and slide toward the knife, means for swinging the arms to move the stones around the guard and into grinding engagement with the knife, means for traversing the stones along the length of the knife and back, means for swinging the frame and slide back to their original position at the end of the grinding cycle, and means for swinging the arms to separate the stones and enable them to pass the guard as the frame and slide are swung back to their original position.

16. In a cloth-cutting machine of the recipro-

cating knife type, the combination of means for sharpening the knife comprising two stones one on either side of the knife, one stone comprising two vertically spaced sections rigidly mounted relative to each other, and the other stone comprising a section lying in a plane intermediate the plane of the two sections of the double stone, means holding the stones in grinding contact with the knife, means for traversing the stones along the length of the knife until the lower section 10 of the double stone has passed beyond the lower end of the knife and then back, the upper section of the double stone engaging the knife after the lower has passed beyond the lower end of the knife.

17. In a cloth-cutting machine of the reciprocating knife type having a guard, the combination of stones for sharpening the knife mounted, when not in use, above the upper end of the knife and beyond the guard, means for rotating the stones, 20 means for swinging the stones around the guard and into grinding engagement with the knife, means for traversing the stones along the length of the knife and back, and means for swinging the stones around the guard and into their original 25 position at the end of the grinding cycle.

18. In a cloth-cutting machine of the reciprocating knife type having a guard, the combination of stones for sharpening the knife mounted, when not in use, above the upper end of the knife 30 and beyond the guard, means for rotating the stones, means for moving the stones around the guard and into grinding engagement with the knife, means for traversing the stones along the length of the knife and back, and means for moving the stones around the guard and into their 35 original position at the end of the grinding cycle.
